CLAIM

The ornamental design for a molded shoe upper, as shown and described.

DESCRIPTION

FIG. 1 is a first perspective view of a molded shoe upper showing our new design;

FIG. 2 is a second perspective view of the molded shoe upper of FIG. 1;

FIG. 3 is a front perspective view of the molded shoe upper of FIG. 1;

FIG. 4 is a rear elevation view of the molded shoe upper of FIG. 1;

FIG. 5 is an elevation view of the left side of the molded shoe upper of FIG. 1;

FIG. 6 is an elevation view of the right side of the molded shoe upper of FIG. 1;

FIG. 7 is a plan view of the top of the molded shoe upper of FIG. 1; and,

FIG. 8 is a plan view of the bottom of the molded shoe upper of FIG. 1.

The broken lines in the figures merely illustrate the environment for the molded shoe upper of the present design and therefore form no part of the claimed design.
